US0D1089562S

(12) **United States Design Patent** (10) **Patent No.:** **US D1,089,562 S**
(45) **Date of Patent:** **** Aug. 19, 2025**

(54) **PLUMBING FITTING**

(71) Applicant: **Lake Products Limited**, Auckland (NZ)
(72) Inventor: **Andrew Leo Haynes**, Helensville (NZ)
(73) Assignee: **Lake Products Limited**, Auckland (NZ)

(**) Term: **15 Years**

(21) Appl. No.: **29/800,612**

(22) Filed: **Jul. 22, 2021**

(51) **LOC (15) Cl.** **23-07**

(52) **U.S. Cl.**

USPC **D23/259**

(58) **Field of Classification Search**

(57) **CLAIM**

The ornamental design for a plumbing fitting as shown and described.

DESCRIPTION

FIG. 1 is a front perspective view of a plumbing fitting, in accordance with an embodiment;

FIG. 2 is a rear perspective view of the plumbing fitting of FIG. 1;

FIG. 3 is a top view of the plumbing fitting of FIG. 1;

FIG. 4 is a bottom view of the plumbing fitting of FIG. 1;

FIG. 5 is a left side view of the plumbing fitting of FIG. 1;

FIG. 6 is a right side view of the plumbing fitting of FIG. 1;

FIG. 7 is a front view of the plumbing fitting of FIG. 1; and,

FIG. 8 is a rear view of the plumbing fitting of FIG. 1.

The broken lines depict portions of the plumbing fitting that form no part of the claimed design.

1 Claim, 8 Drawing Sheets
